UNITED STATES PATENT OFFICE.

THOMPSON M. HUFFMAN, OF DUNKIRK, INDIANA.

COVER FOR SAP BUCKETS.

Application filed June 2, 1922. Serial No. 565,807.

To all whom it may concern:

Be it known that I, THOMPSON M. HUFFMAN, a citizen of the United States, residing at Dunkirk, in the county of Jay, State of Indiana, have invented certain new and useful Improvements in Covers for Sap Buckets; and I do hereby declare the following to be a full, clear, and exact description of the invention, such as will enable others skilled in the art to which it appertains to make and use the same.

This invention relates to new and useful improvements in sap buckets and particularly to covers therefor.

One object of the invention is to provide a cover for a sap bucket which is held firmly in closed position and which can be easily removed a sufficient distance to permit sap being poured from the bucket.

Another object is to provide a cover for a sap bucket which is spring held in closed position and which is also capable of being swung into position at the side of the bucket, when the bucket is to be cleaned or when a number are to be stacked away for storage.

A further object is to provide a cover which will exclude flies, and other insects as well as dust and like foreign substances from the bucket.

Other objects and advantages will be apparent from the following description when taken in connection with the accompanying drawing.

35 In the drawing.

Figure 1 is a rear elevation of a sap bucket made in accordance with the invention.

Figure 2 is a side elevation showing the bucket in tilted position and with the cover moved back, and the spring engaging the lugs.

Figure 3 is a side elevation showing the lid swung into position against the front of the bucket.

Referring particularly to the accompanying drawing 10 represents the body of the bucket having the sap spout receiving opening 11 adjacent the upper edge thereof. Secured to diametrically opposite points on the side of the bucket and adjacent the upper edge are the outstanding lugs 12. Secured to the opposite sides of the bucket, below and slightly in advance of the lugs 12 are apertured ears 13. Disposed on the upper end of the bucket is a cover 14, and secured to

the cover and to the ears 13 are coil springs 15, said springs exerting downward pull on the lid or cover to hold the same firmly on the bucket. This will effectively prevent rain entering the bucket and polluting the sap.

In the operation of the device, the bucket is grasped in one hand and lifted from the tree, after which the lid or cover is raised sufficiently to disengage the flange from the mouth of the bucket, and then pushed back until the springs engage the lugs 12. This will limit the backward movement of the lid, so that a sufficient space is made through which the contents of the bucket may be poured. Attention is directed to the fact that the springs will thus be put under tension, and that upon releasing the lid, the springs will throw the lid back into closed position, with its flange reembracing the mouth of the bucket. The springs and lug not only limit the opening movement of but close it, automatically, and maintain same resiliently.

The peripheral edge of the cover 14 is turned downwardly, as shown at 14', to form a flange, which embraces the mouth of the bucket, whereby effectively excluding flies and other insects. Furthermore, the flange serves to maintain the cover in secure position on the bucket, against being blown open by the wind, thus excluding dust, dirt and rain.

When the bucket is to be cleaned or stored away, the lid is moved into the position shown in Figure 3.

What is claimed is.

1. A sap bucket comprising a body, a cover for the body, resilient connections between the cover and the body for maintaining the cover in closed position, the cover being capable of sliding movement transversely of the mouth of the bucket, and means for limiting the movement of the cover in one direction, to place the resilient means under tension for restoring the cover to closed position.

2. A sap bucket comprising a body, diametrically opposite stop lugs on the body, a flanged cover for the bucket, movable transversely of the mouth of the bucket into open and closed positions, springs secured to the cover and to the sides of the body, and arranged to hold the cover in closed position at times and against the front face of the body at times, the said lugs serving to limit

the opening movement of the cover by engagement of the springs thereagainst, and tensioning of the springs whereby to automatically close the cover when released.

- 5 3. A sap bucket including a body, a cover movable transversely of the mouth of the bucket, resilient means connecting the cover of the body, and means on the body for engagement by the resilient means upon 10 manually moving the cover into open posi-

tion to limit the opening movement of the cover and to tension the resilient means for closing the cover upon being released.

In testimony whereof, I affix my signature, in the presence of two witnesses.

THOMPSON M. HUFFMAN.
